UNITED STATES PATENT OFFICE.

WILLIAM E. RICKEY, OF ROCKY, OKLAHOMA.

ENVELOP.

No. 926,607.

Specification of Letters Patent.

Patented June 29, 1909.

Application filed July 22, 1908. Serial No. 444,812.

To all whom it may concern:

Be it known that I, WILLIAM E. RICKEY, citizen of the United States, residing at Rocky, in the county of Washita and State 5 of Oklahoma, have invented certain new and useful Improvements in Envelops, of which the following is a specification.

The present invention relates to improvements in receptacles of that type which are 10 formed of some flexible material such as paper, and are designed to be closed by means of a sealing flap, and the object of the invention is the provision of novel means which will prevent tampering with or opening 15 of the receptacle after it has been sealed, without leaving traces which would clearly indicate such a procedure.

The invention further contemplates a paper receptacle of this character which is simple 20 and inexpensive in its construction and can be readily sealed or opened in a manner similar to that of an ordinary envelop.

With these and other objects in view that will more fully appear as the description proceeds, the invention consists in certain constructions and arrangements of the parts that I shall hereinafter fully describe, and then point out the novel features thereof in the appended claims.

For a full understanding of the invention and the merits thereof, and to acquire a knowledge of the details of construction, reference is to be had to the following description and accompanying drawing, in which:

Figure 1 is a front view of an envelop constructed in accordance with the invention; Fig. 2 is an enlarged transverse sectional view on the line $x-x$ of Fig. 1; Fig. 3 is a back view of the envelop; Fig. 4 is a plan view of the 40 blank from which the envelop is formed; Fig. 5 is a front view of an envelop embodying a modification of the invention. Fig. 6 is a sectional view on the line 6-6 of Fig. 5.

Corresponding and like parts are referred 45 to in the following description and indicated in all the views of the drawing, by the same reference characters.

For the purpose of illustration, the invention is shown as applied to an envelop, and in 50 the embodiment shown in Fig. 1 the numeral 1 designates the body portion of the envelop, and 2 the flap for sealing the envelop. Integral with this flap 2 is a tongue 3 which is designed to pass through a slit 4 in the back 55 of the envelop, and then through a slit 5 in

the crease at the bottom of the envelop. The tongue is next folded upwardly along the front of the envelop and passed through a slit 6 in the front and a slit 7 in the crease at the top of the envelop. The extremity of 60 the tongue may then be folded rearwardly against the back of the envelop, and is provided with the ears 8 which, when folded outwardly, serve to engage the slit 7 to prevent withdrawal of the tongue. It will also 65 be observed that an intermediate portion of the tongue is formed with similar ears 9 which, when folded outwardly, serve to engage the slit 5 in the crease at the bottom of the envelop. However, when the tongue is 70 being inserted through the various slits, both sets of ears are folded against the back thereof. In the preferred construction of the sealing device, those portions of the tongue 3 upon the outside of the envelop are provided 75 with adhesive, as indicated at 3^a, while those portions of the tongue which are upon the inside of the envelop are provided with adhesive as indicated at 3^b. It will thus be obvious that after the letter or other desired 80 matter has been placed within the interior of the envelop, it is merely necessary to moisten the adhesive upon the flap and tongue, and to insert the tongue through the two pairs of slits, as previously indicated, the ears 8 and 9 85 being subsequently folded outwardly and secured to the envelop by the adhesive applied thereto.

A slight modification is shown in Fig. 5, in which the numeral 1^a designates the body 90 portion of the envelop, and 2^a the sealing flap therefor. This envelop is somewhat longer than that shown in Fig. 1, and the flap 2^a instead of being provided at its central portion with a single tongue, as in the previous 95 instance, is provided with a pair of tongues. The manner of sealing the envelop is identical with that heretofore described, and the two tongues serve to provide a secure closure for the envelop to insure against the opening 100 thereof by an unauthorized party.

From an inspection of Fig. 6 it will be observed that the tongues 3 not only pass through the bottom flap 1^b but also through the end flaps 1^c, thereby holding the flaps together so that the envelop cannot by any 105 possibility be opened without tearing the material of which it is made or otherwise defacing it so as to render such an operation clearly apparent.

Having thus described the invention, what I claim is:

1. An envelop comprising a body portion and a sealing flap formed with a tongue, the body portion being provided with two sets of slits to receive the tongue, and two independent sets of laterally extending ears being provided upon the tongue for coöperation with the slits to prevent withdrawal of the tongue.
- 10 2. An envelop comprising a body portion and a sealing flap formed with a tongue adapted to extend around the back and front of the envelop and have the extremity thereof secured to the sealing flap, slits through

which the tongue extends being provided in both the back and front of the envelop and also in the upper and lower creases thereof, and independent laterally extending ears being provided upon the tongue for coöperation with the slits of the creases in the envelop to prevent withdrawal of the tongue.

In testimony whereof I affix my signature in presence of two witnesses.

WILLIAM E. RICKEY. [L. S.]
